GARTER BELT

Geraldine M. Kimmell, Pasadena, Calif.

Application August 7, 1945, Serial No. 509,382

5 Claims. (Cl. 2—315)

1

This invention pertains to garter belts and hose supporters, particularly for use in various stages of pregnancy.

Garter supporters are usually of the belt type or of the girdle or corset type. The belt type garter supporter has no support value for the abdomen, and the girdle and corset type have a compressive action upon the abdomen. Neither of these types is suitable for wear during pregnancy.

The garter belt of my invention is designed for use in various stages of pregnancy and acts both as a hose supporter and as a cradle for the abdomen. It is so designed that when worn the tension of the garter is carried upon the hips and the line of pull is not across the abdomen. The garter automatically conforms to the contour of the lower abdomen, the hips, and small of the back. The upper portion of the belt is not under any tension or pull and acts merely as a cradle conforming to the curvature of the lower abdomen, hips, and rear.

The formation and function of the garment will be readily understood by reference to the drawing, which shows a preferred embodiment of my garment. In the drawing:

Fig. 1 shows a front view of the garment as it appears upon the wearer;

Fig. 2 shows a side view of Fig. 1;

Fig. 3 is an isometric front view of the garter belt;

Fig. 4 is an isometric rear view of the garter belt; and

Fig. 5 is a plan view of the extended garter belt.

As shown in Fig. 5, the garter belt is made of a rear panel 1, carrying hose rear garter supports 2 and 3. The lower end of the panel 1 between rear left garter 2 and rear right garter 3 is cut arcuately at 4 to fit above the buttocks and conform to the curve of the body. Connected to panel 1 are panels 5 and 6 connected at 7 and 8 by suitable lines of stitching. The panels are of sufficient width with respect to the length to cover the major portion of the lower abdomen. Thus, the panels 4, 5, and 6 may be about one-fourth their length; for example, three to four inches in width. This forms a band of sufficient width to cradle the abdomen. The panels 1, 5, and 6 are cut and attached so that their lower periphery 9 and 10 form an up-sweeping arc or line from the point of suspension of the rear garters 2 and 3 to the ends of the panels 5 and 6. At the extreme lower corners of panels 5 and 6 are suspended front left garter supporters 11 and front right garter supporters 12. As shown in Fig. 5, the point of attachment of these garters to the panel connects above a line connecting the point of attachment

of garters 2 and 3. Positioned at a point intermediate the garter supports 2, 12, 3, and 11 are fastening means consisting of a tape 13 and an eye 14 upon the lower edge of panel 5 and attached at this point to the side next to the body. Positioned at an intermediate point between the garters 3 and 11 upon the lower edge of the panel 6 on the side away from the body are an eye 16 and a tape 15. Upon the extreme corner of the panel 5 opposite the garter 12 are a tape 17 and a hook 18 positioned on the side of the panel 5 next to the body. Positioned at the corner of panel 6 opposite the garter support 11 are a hook 19 and a tape 20 positioned on the side of the panel away from the body.

The edge 21 of the panel 1 may be straight and the edges 22 and 23 of the panels 6 and 5, respectively, are parallel to the arcuate edge 10 of the respective panels. The edges 24 and 25 form an acute angle with the axes of the contiguous garters 12 and 11. The axes of the garters 11 and 12 form an acute angle with the axes of the garters 3 and 2, respectively.

The material is cut as shown in panels on the straight of the material and not on the bias. The panels are cut at the joining ends on a bias so that the seam lines at 7 and 8 run at an angle to the warp and woof. In consequence the weave in panels 5 and 6 runs at an angle to the weave in the panel.

In placing the wrap-around garment on the wearer, panels 6 and 1 are crossed or overlapped, as shown in Figs. 1 to 4. The hook 18 is engaged with the eye 16 and the hook 19 is engaged with the eye 14. The panels 5 and 6 conform with the curvature of the hips and abdomen. As shown in these figures the garter 12 is attached to the panel 5 at a point close to the right hip and the garter 11 is attached to the panel 5 close to the left hip. When the garters are engaged with the hose, pull on all the garters is as shown by the arrows on Figs. 1 and 2. The load caused by the tension on the garters 3 and 4 is carried on the hips and below the abdomen and not across the abdomen, so that substantially no pressure is exerted thereon. The line of pull across the lower part of the panels 5 and 6 is in a direction at a bias to the weave of panels 5 and 6 so that the material stretches to conform with the curvature of the contiguous portion of the body. No appreciable tension appears on the material near the portions 22a and 23a (Fig. 1). The material there while fitting snugly to the curve of the abdomen does not press against the abdomen.

As pregnancy progresses, the distension of the abdomen is accommodated by employing the

tapes. Thus, instead of engaging 19 and 14, the tapes 20 and 13 are employed and instead of using 18 and 16, the tapes 17 and 15 are employed. The functioning of the belt is similar under these conditions to that described above. It will be observed that the spacing of the garters 2 and 3 is not altered by this adjustment. While the spacing of garters 11 and 12 does alter, the degree of necessary adjustment does not make a material difference in the positioning of the hose garters in relation to the pull of hose supporter on the thigh. If the degree of abdominal extension becomes excessive so that the garters 12 and 13 become too close to the crotch, a different size belt may be obtained for the advanced condition of pregnancy.

While I have described a particular embodiment of my invention for the purpose of illustration, it should be understood that various modifications and adaptations thereof may be made within the spirit of the invention as set forth in the appended claims.

I claim:

1. A wrap-around garter belt, comprising a band, a rear right and a rear left garter positioned intermediate the ends of the band extending beyond the rear garters, front left and front right garters attached to the lower corners of the band, one garter at each end of said band, fastening means positioned at each of the corners opposite each of said front garters, said right front and left front garters being spaced from each other upon said belt to be positioned respectively close to the right and left hips of the wearer when the garter belt is in position, fastening means positioned near the lower edge of the band intermediate the left front and the rear right garter and adapted to enter into fastening engagement with the fastening means positioned at the end of the band upon which the right front garter is attached, and additional fastening elements positioned intermediate the rear left garter and the front right garter and adapted to enter into fastening engagement with the fastening means positioned at the end of the band upon which the right front garter is attached.

2. A wrap-around woven band garter belt composed of a rear panel and two side panels, the ends of said panels being cut at a bias to the weave of the panels, each of said side panels being attached to the rear panel at lines of stitching to form a continuous band, a rear right and a rear left garter positioned intermediate the ends of the band, the ends of the band extending beyond the rear garters, front left and front right garters attached to the lower corner of the band, one garter at each end of said band, each corner being positioned close to the hips of said wearer when the belt is in position, fastening means positioned at each of the corners opposite each of said garters, fastening means positioned near the lower edge of the band intermediate the left front garter and the rear right garter and adapted to enter into fastening engagement with the fastening means positioned at the end of the band upon which the right front garter is attached, and additional fastening elements positioned intermediate the rear left garter and the front right garter and adapted to enter into fastening engagement with the fastening means positioned at the end of the band upon which the right front garter is attached.

3. A wrap-around garter belt and abdominal support, comprising a central portion adapted to

fit over the back of the wearer above the buttocks, two end portions attached to said central portion and each of length sufficient to be crossed over the abdomen, the width of the end portions being sufficient to cradle the abdomen with the lower corner of each end adjacent the hips of the wearer, rear garters attached to the lower edge of said central portion, a front garter attached to each of the lower corners of the end portions, fastening means positioned on the lower edge of each of the end portions intermediate the point of attachment to the front and rear garters, and cooperating fastening means positioned on each of the upper corners of the end portions opposite the point of attachment of the front garters.

4. A wrap-around garter belt and abdominal support, comprising a central portion adapted to fit over the back of the wearer above the buttocks, two end portions attached to said central portion and each of length sufficient to be crossed over the abdomen, the width of the end portion being sufficient to cradle the abdomen with the lower corner of each end close to the hips of the wearer, rear garters attached to the lower edge of said central portion, the lower edge of each of said end portions being cut in an upsweeping arc from the point of suspension of each of the rear garters to the ends of said end portions, the front garters attached to each of the lower corners of the end portions, fastening means positioned on the lower edge of the end portions intermediate the point of attachment of the front and rear garters, and cooperating fastening means positioned on each of the upper corners of the end portions opposite the point of attachment of the front garters.

5. A wrap-around garter belt and abdominal support, comprising a back panel made of woven material cut on the straight of the material and adapted to fit over the back of the wearer above the buttocks, two end panels attached to said back panel, the ends of each of the panels being cut on the bias and attached to the other ends on the seam lines disposed at an angle to the warp and woof of the material, said end panels being each of a length sufficient to be crossed over the abdomen, the width of the end panels being sufficient to cradle the abdomen with the lower corner of each end of the panel close to a hip of the wearer, rear garters attached to the lower portion of the end of the back panel, the lower edge of each of the end panels being cut in an upsweeping arc from the point of suspension of each of the rear garters to the end of the end panels, a front garter attached to each of the lower corners of the end panels, fastening means positioned on the lower edge of the end panels intermediate the point of attachment of the front and rear garters and cooperating fastening means positioned on each of the upper corners of the end panels opposite the point of attachment of the front garters.
